UNITED STATES PATENT OFFICE.

ROBERT MINSHULL, OF WATERLOO, WISCONSIN.

STANCHION LOCK.

Application filed May 27, 1921. Serial No. 472,952.

To all whom it may concern:

Be it known that I, ROBERT MINSHULL, a citizen of the United States, and resident of Waterloo, in the county of Jefferson and State of Wisconsin, have invented new and useful Improvements in Stanchion Locks, of which the following is a description, reference being had to the accompanying drawings, which are a part of this specification.

10 This invention relates to stanchion locks particularly to that type of stanchion which in combination with an upper substantially horizontally relatively fixed member is provided with two vertical members, one of 15 which is fixed and the other of which is pivotally connected at the bottom and adapted to swing laterally into open and closed position.

The primary object of this invention is 20 to provide a lock for the swinging member of the stanchion of simple and strong construction which will operate automatically to lock the swinging member in its closed position when the latter is moved thereto 25 and which, furthermore, will reliably and effectively maintain said swinging member in its locked position against the strains set up in the stanchion members by the animal rubbing and pushing thereagainst.

30 A further object of the invention is to provide improved means for releasing the lock which is preferably of such construction that it may be conveniently operated from either side of the stanchion.

35 The invention consists in the novel constructions, arrangement, and devices to be hereinafter described and claimed for carrying out the above stated objects and such other objects as will appear from the following description of certain preferred embodiments illustrated in the accompanying drawings, wherein—

Fig. 1 is a side elevational view of a lock embodying the principles of the invention, certain parts thereof being shown in section and as applied to a stanchion of the type mentioned only certain fragmentary portions thereof being shown;

Fig. 2 is a sectional view taken on the line 50 2—2 of Fig. 1; and

Fig. 3 is a sectional view taken on the line 3—3 of Fig. 1.

Like characters of reference designate like parts in the several views.

55 In the drawings 5 represents the upper substantially horizontally relatively fixed

member and 6 represents the upper end of the laterally swingingly mounted member of the stanchion.

The member 5 is preferably tubular and is 60 provided on its under side with a longitudinally extending slot 7. The member 5 is provided with a catch member which is preferably in the form of a collar 8 adjustably mounted thereon by screws 9. The 65 latch member 10, substantially of the shape shown in Fig. 1, is pivotally mounted on a pivot pin 11 and is adapted to slide in the slot 7 of the member 5 when the swinging member 6 is moved laterally. A pair of 70 outstanding ears or lugs 12 are provided on and adjacent the free end of the latch to limit downward movements thereof. The lower portion of the collar 8 extends across the slot 7, as clearly shown in Fig. 1, and 75 the free end of the latch is beveled at 13 so that the latch will easily ride over the catch when the swinging member 6 is moved into its closed position. A pair of downwardly projecting lugs 14 are provided on 80 the under side of the latch member which are adapted to bear against the respective sides of the catch, as clearly shown in Fig. 1, when the latch is in its locking position.

The means for releasing the latch member 85 from engagement with the catch is mounted on a transverse member, designated as a whole by the reference numeral 15, this member being journaled in a pair of backwardly extending lugs 16 formed on the 90 swinging member 6. The member 15 comprises a central rod or holding member 17 on which a pair of spaced bushings 18 are loosely mounted, the bushings being held in position by washers 19 bearing against the 95 outer ends of the bushings and effectively held thereagainst by upsetting the extremities of the rod member 17, as shown at 20, see Fig. 2. A finger 21 is loosely mounted on the member 17 between the bushings 18. 100 The inner ends of the bushings bear against the respective sides of the finger. In the embodiment shown in Figs. 1 to 3 of the drawings interlocking means are provided between the finger and the bushings, the finger being provided on each side with a pair of laterally extending lugs 22 which are adapted to slip into suitable recesses 23 formed in the bushings 18, see particularly Fig. 3. The free end of the finger 21 projects into a notch 24 formed in the rear of 110 the latch member. By this arrangement it

will clearly be apparent that when the bushings are rotated in a counter clockwise direction the finger 21 will bear down on the rear end of the latch member and lift it out of engagement with the catch. To facilitate rotation of the bushings hand wheels or disks 25 are mounted on the outer ends thereof and rigidly connected thereto by upsetting portions of the ends of the bushings 10 into recesses 25' formed in the disks.

To prevent the latch from being jarred out of its locking position by the animal rubbing or pressing against the stanchion members a spring 27 is preferably provided 15 to hold the latch in locking engagement with the catch. The spring is preferably coiled about the pivot member 11, the end 28 thereof being fixed to the latch and the end 29 thereof being fixed to the stanchion member 6.

In order to prevent strain due to the animal rubbing and pressing against the stanchion member from being transmitted to the latch member, the stanchion member 25 is preferably provided with a pair of up-standing arms 32 which are adapted to slidingly engage the respective sides of the tubular member 5, see Fig. 2.

If desired, a plug 33 may be secured to 30 the member 5 to limit outward movement of the swinging member 6, this plug co-operating with the lugs 12 provided on the free end of the latch and therefore prevents the latch from slipping entirely out of the slot 7. 35 By securing the collar 8 at different points on the member 5 the stanchion may be accommodated to animals of different sizes. From the foregoing description it will be apparent that an automatically operating lock of simple and strong construction has 40 been provided which may be conveniently released from either side of the stanchion.

I claim:

1. In combination, a laterally swingingly 45 mounted stanchion member, an upper hori-

zontal fixed stanchion member, a catch on said fixed member, a latch pivotally mounted on said swinging member, a transverse member mounted in and adjacent the upper end of said swinging member, a finger on said transverse member and operatively connected with said latch, said transverse member comprising a central member and a pair of bushings on said central member, said bushings being loosely mounted on said central member so that their inner ends bear against the respective sides of said latch, and interlocking means on said finger and the inner ends of said bushing to insure turning of said finger and lifting of the latch when said bushing is rotated in the proper direction.

2. In combination, a laterally swingingly mounted stanchion member, an upper horizontal fixed tubular stanchion member, said tubular member having a longitudinally extending slot in its under side, a catch on said tubular member, a latch pivotally mounted on said swinging member and adapted to slide in said slot and into holding engagement with said catch when said swinging member is moved to closed position, a transverse member journaled in and adjacent the upper end of said swinging member, a finger on said transverse member and operatively connected with said latch, said transverse member comprising a central member and a pair of bushings on said central member, said bushings being loosely mounted on said central member so that their inner ends bear against the respective sides of said finger, and interlocking means on said finger and the inner ends of said bushings to insure turning of said finger and lifting of the latch when said bushings are rotated in the proper direction.

In testimony whereof, I affix my signature.

ROBERT MINSHULL.
